UNITED STATES PATENT OFFICE.

PETER BUBELIS, OF PORTSMOUTH, NEW HAMPSHIRE.

LOCOMOTIVE FIRE-BOX ARCH.

Application filed May 1, 1925. Serial No. 27,320.

This invention relates to an improved arch for installation in the fire box of a locomotive, and it has more particular reference to a metallic arch of hollow construction provided to permit the heated boiler water to be circulated therethrough.

The invention is characterized by the provision of an arch which is made up of duplicate half sections spaced apart and forced into tight contact with the fire box wall through the use of a parting wedge.

It follows also that inasmuch as the circulating water must be obtained from the water space around the fire box and circulated back to that space, an advantage is derived from the use of novel means for providing fluid tight connection of the circulating tubes with the walls defining said water space.

The specific details constituting the novel arrangement of parts will become apparent during the course of the following description of the drawings.

In the accompanying drawings forming a part of this application, and in which like numerals are employed to designate like parts throughout the same:

Figure 1 is a vertical fragmentary section of a locomotive fire box showing portions of the flues and showing the improved arch and circulating means in association therewith.

Figure 2 is an enlarged cross section taken through the arch, the section being made approximately upon the plane of the line 2-2 of Figure 1.

Figure 3 is a horizontal section through the upper portion of the fire box looking downwardly, and showing the improved construction in top plan.

Figure 4 is an enlarged detail section of a packing gland, and means for connecting the same in place.

Referring to the drawings in detail, the reference character 1 designates, as a whole, a portion of a locomotive showing more particularly the construction of the fire box 2. As is usual, this fire box is surrounded by a water space 3 defined by spaced parallel inner and outer walls. The inner and outer side walls are represented by the reference characters 4 and 5 respectively, the inner and outer rear walls by 6 and 7 respectively, and the front walls by 8 and 9 respectively. The wall 6 is sometimes designated as the flue sheet in that it supports the usual flues 10,

the wall 7 being also known as the throat sheet. These parts however constitute a portion of the usual locomotive boiler construction, and form no part of the present invention.

The invention as before intimated comprises an improved arch for location in the fire box 2. This arch is intended to supplement the customary brick arch frequently used. In carrying out the invention, the side walls 4 of the fire box are provided with lugs 11 upon which the arch sections, designated generally by the reference character 12 are adapted to rest. The arch is composed of a pair of duplicate half sections 13, these being of hollow formation, and being formed of metal sheets appropriately welded and riveted together. Each section embodies a substantially horizontal portion, and an upwardly offset portion. Also, the opposed longitudinal sides of the half sections, which are spaced apart, are inclined to provide for reception of a parting wedge 14. Obviously, when this wedge is forced between the sections, they are pressed into tight contact with the walls 4 of the fire box.

The heated water from the water space 3 is adapted to be circulated through this hollow arch and in accomplishing this, I make use of a forward pair of pipes 15 and a rear pair of pipes 16, the last named pipes being comparatively short. The inner ends of the pipes are connected to the arch to provide fluid tight joints and at the points of connections are U-shaped clips 17 riveted to the arch sections. As shown in Figure 4, the outer end of each pipe is fitted into a packing gland 18 which is tapped into the adjacent wall, for instance the flue sheet 6. This gland includes an outer shell 19 internally screw threaded to receive a pipe retaining nipple 20, and a centrally apertured screw threaded disc 21. It is provided at its enlarged end with an inclined flange 22 and this flange is adapted to abut a correspondingly shaped flange 23 on the inner end of a screw threaded sleeve 24 which is threaded through an opening in the throat sheet 7. This sleeve is provided with a plurality of water passages 25 disposed between the walls 6 and 7 and a closing cap 26 is threaded onto the external end thereof, packing 27 being located between the sleeve and the cap.

From the foregoing arrangement, it is obvious that the hot water in the circulating

space of the boiler will be permitted to pass through the openings 25 in the sleeves 24 and thence through the circulating pipes 16, after which it flows through the arch and pipes 15.

5. It is thought that the description taken in connection with the drawings will enable persons skilled in the art to which the invention relates to obtain a clear understanding of the same, and to appreciate the advantages derived from a construction of this kind. Therefore, a more lengthy description is thought unnecessary.

10 While the preferred embodiment of the invention has been shown and described it is 15 to be understood that minor changes coming within the field of invention claimed may be resorted to if desired.

Having thus described the invention, what I claim as new is:—

- 20 1. In combination, a fire box, water legs at opposite sides of the same, a water container in the fire box and comprising hollow spaced sections the outer portions of which are disposed on supports on opposite walls 25 of the fire box and the inner edges of which are beveled, and a downwardly tapered wedge interposed between said beveled edges of the sections and extending throughout the length of said sections and arranged with its 30 upper and lower sides flush with the upper and lower sides of the hollow sections, and conduits at opposite ends of and complemen-

tary to each section; said conduits connecting the sections with the water legs and being open at their ends to the interiors of the 35 container or hollow spaced sections and the interiors of the water legs.

2. In combination, a pair of spaced walls defining therebetween a water circulating space, a tube extending through an aperture 40 in one of the walls and into said space, the opposite wall having an opening aligned with and coincident with the end of the tube, removable means normally closing said opening, a packing gland disposed in said space 45 and connected with said closing means and secured in the wall through which the tube extends and about said tube, said gland surrounding the tube within said space, and an annular means secured in said gland and adapted 50 to retain packing in the gland and about the tube.

3. In a structure of the class described, a packing gland threaded and thereby adapted to be tapped into a screw threaded opening 55 in a supporting wall, and a sleeve, said gland and sleeve being provided with cooperating connecting flanges and said sleeve being closed at its outer end by a removable cap and being provided between its ends with 60 water circulating openings.

In testimony whereof I affix my signature.

PETER BUBELIS.
